COMBINED ELECTRIC FAN AND AIR HEATING MEANS

John M. Aufiero, Plandome, N. Y., assignor to
E. A. Laboratories, Inc., Brooklyn, N. Y., a corporation of New York

Application September 19, 1946; Serial No. 697,857

5. Claims. (Cl. 219—39)

1.

This invention relates to an improved fan unit for air circulation, and has as its principal object, the provision of a combined fan and heater unit which is guarded against damage to rotating or operating parts, will not constitute a fire hazard when used as a heater, and will not be dangerous for use in homes in which there are small children.

Electric fans are commonly provided with guard means about the rotating fan blades. Generally, the guard means comprise wire structures having very large openings, and inefficiently guard against the accidental or wilful insertion of foreign objects into the fan area. The motors—and where used, the motor oscillator—are usually unprotected. It is not an infrequent occurrence for draperies or other hanging objects to be blown or drawn between the openings of the guard to become entangled with the blades of the fan, or to catch on the mechanism by which the fan is oscillated to and fro. Children have been known to poke their fingers into the whirling blades of the fan. When, as has been proposed, heating coils or other heat producing elements are arranged in conjunction with the fan so that warmed air may be circulated throughout the room, the hazard becomes additionally great because of the fact that draperies or other inflammable objects which may be drawn into the fan may catch fire, or the fan, if knocked over, may by heat radiation or conduction, ignite the object on which it has fallen.

Pursuant to the present invention, a fan having an optionally usable heating element, is provided with an improved casing or housing which does not materially interfere with air flow, but does provide complete protection against the hazards enumerated above. Among the several objects of the invention, therefore, are:

To provide an electric fan having a safety casing provided with guard means which afford complete protection against the entry of foreign objects, but are nevertheless easily removable to permit access to the interior for replacement or repair of the respective elements of the fan and heater unit;

To provide a combined fan and electric heating unit having a heating element operable conjointly with the fan to provide a gentle, enforced warm air circulation;

To provide a combined fan and heater wherein the heat coils or the like may easily be removed as a unit without affecting the operation of the fan;

To provide a combined fan and heater having

2.

means whereby a portion of the heat coils may be optionally disconnected when desired to reduce the power consumption thereof;

5. To provide a unit having heating and air circulating means which may be optionally oscillatable or adjusted to any vertical angle of discharge within predetermined limits;

To provide an air circulation means having an oscillating mechanism whereby the air stream is caused to traverse a predetermined arc and wherein the oscillating mechanism is enclosed within the safety casing to protect it against damage or from being fouled by objects entering the casing;

10. To provide a fan oscillating mechanism which may be rendered non-operative at will by a simple means which is accessible from the outside of the casing; and

15. To provide an air circulation unit embodying a fan and heat coil means, fully protected by a substantial guard construction which does not interfere with the inclination of the unit or the oscillation thereof.

20. Other features and advantages of the invention will be apparent from a study of the annexed drawings and the description relating thereto.

In the accompanying drawings:

Fig. 1 is a front view; the fan blades having been removed to reveal structure hidden thereby, and with a portion, only, of the front guard grille being shown;

30. Fig. 2 is a side elevation of the structure, partly in section;

35. Fig. 3 is a detail section on lines 3—3 of Fig. 1, showing the insulator mountings for the heat coil unit;

Fig. 4 is a top plan view of the oscillating mechanism with the cover portion thereof removed to show internal structure;

40. Fig. 5 is a vertical sectional elevation of the oscillating-mechanism control on line 5—5 of Fig. 4, at one stage of operation thereof;

Fig. 6 is a schematic wiring diagram showing the fan control and heater control; and

45. Fig. 7 is a modified wiring diagram showing an optional arrangement whereby half of the heating coils may be disconnected from the circuit.

Referring to the drawings, the combined heater and air circulator 10 is supported upon a relatively heavy base 11 of adequate area and preferably provided with holes (not shown) to permit the base to be secured to a wall or other vertical surface. A standard 12 is pivotally secured to the base, as on the screw shaft 14, so that the standard may be inclined from the ver-

tical if desired. Preferably a set screw 15 or equivalent is utilized to retain the standard 12 in its adjusted position.

Supported upon the standard 12 so as to be rotatable thereon is a fan motor 16, which may have a conventional oscillation drive 17 which, as is known in the art, has a power-driven eccentric 18 and a crank arm connection 19 with the standard. The oscillating mechanism is preferably normally set so as to be non-operative, whereby the fan motor is stationary upon its standard, but through the agency of a setting means 20, later described, the fan motor automatically oscillates through a predetermined arc.

The fan blades 21 are of any conventional construction.

At the front and rear faces of the fan motor, and supported thereon by screws 22 which enter suitable lugs provided in the motor casing, are arcuate support frames 23, 24 which together form the structure for supporting the casing and the heat coil. The said frames 23, 24 are of such frontal configuration, see Fig. 1, as to secure three brackets 25, 26, 27 which extend substantially radially at mutual angles of 120 degrees. Each bracket has at its lower portion an ear 28 which may fit within the spaced frames 23, 24, for attachment thereto by screws or equivalent; and also has at its outer end a flange 30 which engages with the inside wall of the casing 31 and is affixed thereto by rivets or the like.

As appears in Fig. 2, the respective brackets are substantially triangular, with a wide base firmly affixed at the motor, and a single point of contact with the casing 31. Such construction affords rigidity of casing support, while effectively reducing transmission of motor vibration.

As is apparent from the opening 32 through which the standard 12 passes, the casing may freely oscillate with the fan motor.

The heat coils 33 are advantageously carried by the lower brackets 26, 27, on an angularly V-shaped frame having side members 34, 35 which are preferably screwed to lugs 36, 37 provided on the respective brackets. Said side members are interconnected by a transverse brace 36', said brace having, near its ends, the spaced pairs of interfitting insulators 38, 39 which by means of the illustrated machine screws or equivalent insulatedly secure brackets 40 to the terminals 41 to which are attached the ends of the heat coils and the respective interconnecting and power leads 42, 43. A connector block 44 mounted on the standard 12 provides terminal connections for the power leads 43. At the upper end of the support members 34, 35 are insulating spacer blocks 45 supporting the upper ends of the heat coils. In Fig. 1, the respective heat coils are in series, as shown in Fig. 6. An intermediate insulating spacer 46 is secured to each of the supports 34, 35 for additional heat coil support.

The heat coils, as appears in Fig. 2, occupy a vertical plane behind the fan 21, substantially centrally of the casing.

The casing 31 is enclosed at its ends by the inwardly flanged grille supports 47, removably affixed to the casing by suitable means such as sheet metal screws. The guard grilles at each grille support include a plurality, preferably four, of groups of rods 48 which affix at one end to the respective grille supports and extend radially inwardly. Interconnecting the said groups of rods 48 are a plurality of rods 49 concentrically arranged upon, and preferably spot-welded to,

said radial groups. Rods 49 are sufficiently spaced to completely protect the interior of the casing against the introduction of any large foreign objects such as draperies, curtains or the like, and to make it difficult for a child to insert his fingers sufficiently to strike the fan blades. The relatively small diameter of the rods does not materially interfere with the flow of air through the casing.

10 The center casing portion 31 is ventilated by blanking out a plurality of openings 50 which commence in an area beneath the heat coil mount and continue about the periphery of the casing to an area adjacent the handle 51 affixed thereto. 15 In an extreme circumstance wherein the device may have been knocked over on its face with the fan and heat coils in operation, so as to block off normal axial air flow through the casing, the ventilating openings 50 will permit sufficient outward movement of air to prevent overheating of the heat coils and undesirable or dangerous rise of casing temperature. The central disposition of the connector block 44 and that location of the leads 42, 43, well behind the fan 21 makes it 20 an almost impossibility to reach the block or leads, without first removing the fan.

It will be seen that the heat coils are easily removable as a unit by detaching the front grille mount 41 and the fan blades 21, whereupon the 30 screws affixing the heat coil mounting structures to the lugs 36 are accessible. The leads 43 of the coils are readily available for disconnection from the block 44. It is contemplated that jack and plug connections may be used for easy attachment and removal of the leads 43 from the block, although the high wattage performance of the heat coils may require the better electrical connection afforded by standard screw binding posts.

Referring now to Figs. 6 and 7, two optional 40 wiring diagrams are shown. Fig. 6 discloses the heat coils 33 in series connection and it is presently contemplated that the coils will draw 2600 watts for such installations as factories or offices where heavy duty wiring is available. In the Fig. 7 45 circuit the heat coils are arranged in two series-connected pairs, with a separate switching means to disconnect one pair to reduce the current demand to 1300 watts to conform to standard residential wiring.

50 In the Fig. 6 circuit, the double pole, single throw heat coil switch 55 has a lead 56 connected to one of the main power source leads 57 and a lead 58 which, through the agency of the connector block connects to one of the leads 43 in the 55 series heat coil circuit. The right hand lead 43 as viewed in Fig. 6 connects through the block 44 to the other lead 59 of the main power source.

The motor 16 is controlled by a switch 60, the central pole of which is connected to power 60 source lead 57. Switch 60 has three positions which individually connect by the leads 61, 62, 63 to winding of a choke 64. From the uppermost switch position a lead 65 connects through the block 44 to a motor lead 66. The return motor 65 lead 67 connects to the block 44 and thence through conductor 59 to the power supply.

Considering first motor operation in absence of heat coil operation, the switch 55 will be in "off" position, and no current will flow to the heat coils. 70 The motor switch in its first position passes through conductor 61, the full choke winding, thence through conductors 63, 65 and 66 to the motor. The resistance of the choke winding will operate the motor at its lowest speed, say 1000

75 R. P. M. At the second position, one half of the

choke winding is cut out, providing a speed of 1200 R. P. M., and at the top position, the choke is out of the circuit and the motor will operate at full 1400 R. P. M. speed.

It will be noted that the second pole of switch 55 is connected through lead 68 to the opposite choke winding, and thence through lead 70 to a junction with lead 61. With switch 55 thrown to "on" position, the heat coils will be energized, and the motor will be energized through the choke and the conductors 63, 65, 66, even though the motor switch 60 is open. In this condition of operation, the motor speed will be about 700 R. P. M. The motor speed may be increased as desired, even with the heat coils in operation, by throwing its switch 60 to the appropriate speed position, whereupon the effect of the choke 62 will be appropriately reduced. With the two switch combination, therefore, four motor speeds may be attained with the heat coils in operation.

In the circuit of Fig. 7, one pole of switch 55 connects through lead 58 and connector block 44A to lead 43 to the innermost of the left hand heat coils 33, which is in series with the innermost right hand coil, thence through conductor 43 and block 44A to conductor 59. The outermost pair of coils connects from lead 58 through lead 71 to a single-pole single throw switch 72, from which lead 73 connects to block 44A and thence through lead 43A to the outermost heat coil 33 of the left hand group. The series-connected outer right hand coil 33 connects to lead 43 and thence to conductor 59.

It will be seen that the heat coils can be energized only when switch 55 is closed and that the outer coils 33 can be energized only when switch 72 is closed. Thus, either both or only one of the heat coil pairs may be energized.

The motor control is as previously described.

As indicated in dotted line in Fig. 2, the respective switches and choke are preferably mounted within the base 11.

Referring now to the oscillating control 17, Fig. 4 discloses the motor shaft 75 terminating in a worm gear 76 continually in mesh with the gear 77 fixed to a shaft the opposite end of which has a worm gear 78. Gear 78 is continually in mesh with a cooperating gear 80 which is freely rotatable on a vertical shaft 81 and rests on a shoulder 82 formed on said shaft. So long as the motor is in operation, the gear 80 will be in rotation.

The upper end 83 of shaft 81 is threaded and receives a cooperatively threaded sleeve 84. Disposed intermediate the bottom of said sleeve and the upper surface of gear 80 is a friction washer 85. Extending axially upwardly from sleeve 84 is a shaft 86 to which is keyed a bevel gear 87, the teeth of which are substantially higher than standard.

A bracket 88 fixed to the casing of the oscillating mechanism journals a shaft 90 having at its end a bevel gear 91 for cooperation with gear 87. Gear 91 also has abnormally high teeth. A coil spring 92 disposed between the bracket and the knob 20 normally urges the shaft 90 to the right of Fig. 5, into a position wherein the gears 87 and 91 are not in mesh.

When oscillation of the fan is desired the knob 20 is pushed inwardly to a position where gears 87 and 91 are in mesh. Upon rotation of the shaft in the proper direction the sleeve 84 will screw downwardly along the end 83 of shaft 81, whereupon the end of said sleeve will tightly confine the friction washer 85 against the surface of gear 80, which in turn will clamp the 75 fan, heat coil unit, motor and motor oscillating

gear against the surface of the shoulder 82. Knob 20 is then released and the gears 87 and 91 disengage. Then, when the motor is started, shaft 82 and its thereto attached eccentric will rotate to oscillate the fan in conventional manner.

When fan oscillation is not desired the knob 20 (the motor having previously been stopped) is pushed forward against the tension of its spring to bring gears 86 and 91 into mesh, whereupon rotation of the gear 91 in the necessary direction will unscrew upon threaded end 83, relieving the pressure on the friction washer 85 and restoring gear 80 to its normal free rotation on shaft 81. The purpose of the abnormally high teeth on the respective gears 87 and 91 is to permit a sufficient upward movement of the sleeve 84 during the unscrewing thereof.

As previously stated, the oscillating mechanism is protective housed within the casing. The knob 20 projects outwardly through the rear grille, as shown in Fig. 2, for ready accessibility. The knob does not rotate, inasmuch as the gear 91 is normally disengaged from gear 87; hence there are no exposed moving parts to become entangled with foreign objects which may be in the proximity.

Although the invention has been described by making a fully detailed reference to the certain presently preferred embodiments, such detail of description is to be understood in an instructive rather than a limiting sense, many changes being possible within the scope of the claims here-to appended.

I claim:

35 1. Air circulation means comprising a motor mounted upon a standard; a fan fixed to the shaft of said motor; a pair of frames fixed to the motor at opposite ends thereof; a plurality of substantially triangular brackets affixed at their bases to said frames and extending approximately radially outwardly from said motor, and a casing supported upon the apices of said triangular brackets and concentric with said motor, said casing completely encompassing said fan and said motor and having at its opposite ends closely spaced grille means to permit air flow while precluding the entry of any relatively large foreign objects.

40 2. Air circulation means comprising a motor mounted upon a standard; a fan fixed to the shaft of said motor; a pair of frame members affixed to the opposite end walls of the motor casing; triangular bracket means disposed between said frame members and affixed thereto to extend radially outwardly from said motor; a heat coil insulatedly carried by said bracket means behind said fan; and a casing supported upon the apex ends of said brackets and concentric with said motor, said casing completely 45 encompassing said fan, heat coil, and motor, and having at its opposite ends removable grille means to preclude the entry of any large objects into said casing.

45 3. Air circulation means comprising a motor 50 swivelly mounted on a standard; means actuated by said motor for causing the same to oscillate on said standard; a fan fixed to the shaft of said motor, bracket means secured to said motor and extending radially outwardly therefrom; a heat coil unit removably secured to said bracket means forwardly thereof in the path of air flow resulting from fan operation; and a casing supported by the ends of said brackets concentric with said motor and completely enveloping said 55 fan, heat coil unit, motor and motor oscillating

means; said casing having removable grilles at its opposite ends to permit access to the points of securement of said heat coil unit to said brackets.

4. A combined electric fan and air heating means, comprising a base, a standard tiltable on said base, a motor mounted on said standard, said motor having a fan affixed to the shaft thereof; brackets secured to said motor and extending radially thereof; a frame removably secured to said brackets at the ends thereof; a heat coil carried by said frame behind said fan; a connector block mounted on said standard to afford means of detachably connecting said heat coil to an external power source, whereby said heat coil and its supporting frame may be removed as a unit from said brackets; a motor circuit electrically connected with said heat coil circuit, whereby when said heat coil is energized said motor will operate; a switch in said combined motor and heat coil circuit; a separate switch in said motor circuit for operation of said motor independently of said heat coil; and a casing carried by said brackets and enclosing said fan, heat coil, motor, and connection block to preclude access thereto.

5. A combined fan and heating means, comprising a base, a standard tiltable on said base, a motor mounted on said standard, and a fan

removably secured to the shaft of said motor; support plates fixed to said motor at the ends thereof; brackets fixed to said support plates and extending radially from said motor, the respective front edges of said brackets being in a common plane behind and substantially parallel to the plane of said fan; a substantially U-shaped frame removably secured to said brackets at the front edges thereof and having leg members extending upwardly on each side of said motor within the circle of rotation of said fan; electric heat coil means insulatedly supported on said frame; a casing supported by said brackets at the ends thereof and completely enveloping said fan, heat coil means and motor; and removable grille means at the respective ends of said casing to afford access to the means for securing said heat coil frame to said brackets.
